W. C. DEVEREAUX

DOOR LATCH

Filed Sept. 11, 1922

FIG. 1

Fig. 3.

Inventor

WILLIAM C. DEVEREAUX

By Whitemore & Bush Whitemore & Bushway.

Attorneys.

UNITED STATES PATENT OFFICE.

WILLIAM C. DEVEREAUX, OF DETROIT, MICHIGAN, ASSIGNOR TO FERRO STAMPING & MANUFACTURING COMPANY, OF DETROIT, MICHIGAN, A CORPORATION OF MICHIGAN.

DOOR LATCH.

Application filed September 11, 1922. Serial No. 587,444.

To all whom it may concern:

Be it known that I, WILLIAM C. DEVEREAUX, a citizen of the United States of America, residing at Detroit, in the county of Wayne and State of Michigan, have invented certain new and useful Improvements in Door Latches, of which the following is a specification, reference being had therein to the accompanying drawings.

10 The invention relates to door latches and has particular reference to latches for use in metallic vehicle doors. One of the objects of the invention is the provision of a simple latch construction comprising but 15 few parts which may be cheaply manufactured. Another object is the provision of a curved pivoted lever engageable with a shoulder upon the sliding bolt and arranged at right angles to its axis, this lever having 20 a convex bearing on the inner side of its curve engageable with the shoulder to move the bolt longitudinally in one direction upon rotation of the lever in one direction. A further object is to provide a bearing upon 25 the latch for the outer end of the operating shank of the latch handle. Other objects of the invention reside in the novel features of construction and combinations and arrangements of parts as more fully hereinafter set forth.

30

In the drawings:

Figure 1 is a side elevation of a door with my latch applied;

Figure 2 is a cross section on the line 2—2 35 of Figure 1;

Figure 3 is a perspective view of the latch;

Figure 4 is a cross section on the line 4—4 of Figure 1.

40 1 is the metallic vehicle door having the inner and outer panels 2 and 3 respectively.

4 is the latch of this door having the case plate 5 with the transversely extending flange 6 at its forward edge and the channel-shaped cover plate 7 which cooperates with the case plate to guide the longitudinally movable bolt 8 and inclose the coil spring 9. The nose of the bolt 8 extends through the transverse flange 6 and the coil

45 spring abuts the inner end of the bolt and the transverse end flange 10 of the cover plate.

50 11 is a lever pivoted to the case plate at its lower end and extending between parallel shoulders 12 and 13 formed in the bolt

8. 14 is a rotatable hub member journaled between the case plate 2 and the laterally extending flange 15 upon the cover plate 7, this hub member having a portion engageable with the lever 11 to rotate the same 60 rearwardly about its pivot upon corresponding rotation of the operating shank 16 non-rotatably secured at its inner end in the hub member and to the outer end of which is secured the door handle 17. To permit of 65 using parallel shoulders upon the bolt which extend at right angles to the longitudinal axis of the bolt, thereby decreasing the cost of production, and at the same time to permit of using an actuating lever which is 70 curved, this lever 11 has intermediate its ends and on the inner side of its curve the convex bearing portion 18 which is engageable with the shoulder 12 of the bolt.

To normally retain the actuating lever 11 and the hub member 14 in inoperative position, I have provided the flat substantially U-shaped spring 19, one end of which abuts the edge of the lever 11 at the inner side of its curve and the other end of which abuts the transverse lower side flange of the cover plate 7, the rounded or base portion of this spring being pivoted about the tongue 20 formed in the lower flange by cutting parallel slots therein.

The channel-shaped cover plate 7 is preferably formed of sheet metal and is secured to the case plate 5 by lugs upon the transverse end and side flanges as well as the laterally extending flange which extends 80 through the case plate and are clinched thereover.

To form a bearing for the operating shank 16, I have provided the yoke 21 having the foot flanges secured to the laterally extending flange 15 and base of the channel-shaped cover plate 7. This yoke is provided with a cylindrical threaded flange 22 in alignment with the opening through the lateral flange 15 and case plate 2 for the passage of the operating shank. 23 is a bearing in which the operating shank is rotatably mounted at its outer end, this bearing threadedly 95 engaging the threaded cylindrical flange and extending outwardly beyond the outer panel 100 3 of the door 1. The operating shank is journaled at its inner end by reason of the fact that it is non-rotatably secured in the rotatable hub member 14 which in turn is 105 journaled in the lateral flange 15 and case.

110

plate 2. Thus, it is seen that with this arrangement separated aligned bearings upon the latch are formed for the operating shank of the door handle. Also, that the outer bearing may be attached after the door has been enamelled and baked so that its finish will not be marred.

What I claim as my invention is:

1. In a door latch, the combination with 10 a case plate, of a longitudinally slidable bolt, a cover plate cooperating with said case plate to guide said bolt, said cover plate having a tongue formed therein, a lever pivoted to said case plate and engageable with said bolt to move the same in one direction, and a substantially U-shaped spring having one end engageable with said lever to hold the same normally in inoperative position, and the other end engageable with said cover plate, the base of said spring extending around said tongue.
2. In a door latch, the combination with 25 the case plate, of a longitudinally slidable bolt, a cover plate secured to said case plate and cooperating therewith to guide said bolt, said cover plate having a laterally extending flange spaced from said case plate, a lever pivoted to said case plate and engageable with said bolt to move the same 30 in one direction, a rotatable member journaled between said case plate and laterally extending flange and engageable with said lever to actuate the same, an operating shank in engagement with said rotatable member, and a yoke upon said cover plate and provided with a bearing spaced from 35 said rotatable member for said operating shank.
3. In a door latch, the combination with 40 the case plate, of a longitudinally slidable bolt, a channel shaped cover plate secured to said case plate and cooperating therewith to guide said bolt, said cover plate having a laterally extending flange spaced from 45 said case plate, a lever pivoted to said case plate and engageable with said bolt to move the same in one direction, a rotatable member between said laterally extending flange and case plate and journaled therein for 50 actuating said lever, an operating shank engaging said rotatable member, and a yoke having foot flanges secured to the base of said cover plate and to said laterally extending flange and provided with a bearing 55 for said operating shank.
4. The combination with a door having spaced inner and outer panels, of a latch secured to said inner panel comprising a case plate, a longitudinally slidable bolt 60 upon said case plate, a cover plate secured to said case plate and cooperating therewith to guide said bolt, a lever pivoted to said case plate and engageable with said bolt to move the same in one direction, a 65 door handle operating shank extending

through said outer panel, a rotatable member journaled upon said case plate and adapted to actuate said lever, said rotatable member forming a bearing for the inner end of said operating shank, a yoke secured to said cover plate, and a bearing for the outer end of said operating shank insertable through said outer panel into engagement with said yoke.

5. In a door-latch, the combination with 75 the case plate, of a longitudinally slidable bolt, a cover plate attached to said case plate and having a laterally extending flange spaced from said case plate, means for moving said bolt in one direction, and 80 operating shank engageable with said means, and a yoke having foot flanges secured to said cover plate and said laterally extending flange being provided with 85 a bearing for the operating shank.

6. In a latch of the class described, the combination with a case plate, of a bolt movable thereon, a cover plate for said bolt having a laterally extending flange, a lever pivoted on the case plate adapted to actuate the bolt, a hub member for moving the lever, an operating shank for the hub member, a yoke secured to the cover and laterally extending flange, and a bearing for the shank detachably secured to said yoke.

7. In a latch of the class described, the combination with a case plate, of a bolt movable thereon, a cover plate for said bolt having a laterally extending flange, a lever pivoted on the case plate adapted to actuate the bolt, a hub member for moving the lever journaled in the case plate and laterally extending flange, an operating shank for the hub member, a yoke secured to the cover and laterally extending flange, and a bearing for the shank detachably secured to said yoke.

8. In a latch of the class described, the combination with a case plate, of a bolt movable thereon, a cover plate for said bolt, a lever pivoted on the case plate adapted to actuate the bolt, a hub member for moving said lever, an operating shank for the hub member, a yoke secured to the cover and having a cylindrical flange, and a bearing for the shank detachably secured to the cylindrical flange of said yoke.

9. In a latch of the class described, the combination with a case plate, of a bolt movable on the case plate having spaced parallel shoulders, a curved lever pivoted on the case plate and extending between said shoulders, said lever having a convex bearing portion on the inner side of the curve engageable with one of said shoulders for actuating said bolt, and means for moving said lever.

In testimony whereof I affix my signature.

WILLIAM C. DEVEREAUX.
